JACK FOR SOLE PRESSING MACHINES

Charles F. Fitzgerald, Beverly, Mass., assignor to
 United Shoe Machinery Corporation, Flemington, N. J., a corporation of New Jersey

Application June 28, 1947, Serial No. 757,757

19 Claims. (Cl. 12—33)

1

This invention relates to machines for use in the manufacture of shoes and is herein illustrated as embodied in a machine for applying pressure to shoe bottoms, for example, to press or lay a sole member upon the bottom of a shoe on a last.

A machine commonly used in pressing or laying soles on the bottoms of lasted shoes is one of the type illustrated in Letters Patent of the United States No. 1,920,977, granted August 8, 1933, upon an application filed in the name of Sidney J. Finn. In a machine of that type the lasted shoe and a sole are placed in a pressure box provided at the top with a flexible diaphragm upon which the sole and shoe are mounted. Fluid, such as water, is then forced into the pressure box to distend the diaphragm and wrap it tightly around the sole and lower portion of the shoe, the shoe being supported against the pressure applied through the diaphragm by a jack provided with suitable abutments for engaging the toe portion of the shoe and the top of the last at the heel portion of the shoe.

In machines of the type referred to the jack is normally located in a position at one side of the pressure box and it is swung laterally into operative position over the diaphragm during the operation of the machine after the shoe has been placed upon the diaphragm, the shoe being moved slightly upwardly by the machine to press it firmly against the jack abutments before the diaphragm is distended to apply pressure to the shoe bottom.

The toe abutment or pad of the jack in such machines is moved into clamping relation with the toe portion of the shoe automatically before pressure is applied to the shoe bottom by mechanism fully disclosed in the patent referred to, this mechanism locking the toe pad against upward movement during the pressure applying operation. It is desirable, however, in order to prevent the heel end of the shoe from tilting or lifting away from the diaphragm when pressure is applied to the shoe bottom, to locate the other abutment of the jack, that is, the post which engages the top of the heel portion of the last in the shoe, in actual engagement with the last before any pressure is applied to the shoe bottom. However, it is also necessary, in order to provide sufficient space between the jack post and the top of the last to permit the jack to swing over the pressure box when the shoe is mounted therein, to maintain the jack post in an elevated position until after it is swung into position over the pressure box so that the jack post will always

2

clear the top of the last when it is swung over the box irrespective of the size or height of the particular last being used.

In accordance with one of its features, the present invention provides improved means for accomplishing this result which, as illustrated, maintains the heel abutment or jack post in a retracted or elevated position while the jack is being swung into operative position over the pressure box having a shoe mounted therein and moves the jack post into operative engagement with the top of the last in the shoe before pressure is applied to the shoe bottom. As herein illustrated, the means for moving the jack post into engagement with the top of the last preferably comprises a wedge positioned between the jack and jack post and arranged for sliding movement transversely or laterally thereof so that, when the wedge is moved in one direction, the jack post is brought into engagement with the last in the shoe, and, when the wedge is moved in another direction, the jack post is moved away from the last and returned to its initial or inoperative position.

In accordance with another feature of the invention, the wedge is moved to operate the jack post automatically and in predetermined timed relation to the operation of the rest of the machine and, more particularly, in timed relation to the application of pressure to the shoe bottom. As illustrated, the wedge is actuated to move the jack post into operative engagement with the last in the shoe after the jack has been swung laterally into operative relation to the pressure box but before the diaphragm is distended to apply pressure to the shoe bottom. Accordingly, the jack post will clear the top of the last as the jack is swung into operative position relatively to the shoe irrespective of the height of the last while, on the other hand, the heel end of the shoe will be prevented from lifting or raising away from the diaphragm during the pressure applying operation, particularly at the start of such operation, because the jack post will have been moved into actual engagement with the last before any pressure has been applied to the shoe bottom.

As herein illustrated, the means for accomplishing these results automatically and in the timed sequence referred to comprises mechanism, including a bell-crank lever and a solenoid for operating said lever, constructed and arranged, upon energizing of the solenoid, to move the wedge laterally in one direction between the jack and jack post. In order to energize the solenoid at the proper time, a micro-switch is provided which

is operated to open and close a push button switch by further mechanism arranged to co-operate with a portion of the machine associated with the pressure applying mechanism so that the micro-switch will be operated at exactly the right time with respect to the pressure applying operation. Accordingly, the jack post is moved automatically into operative engagement with the last in the shoe after the jack has been swung into operative position relatively to the pressure box and shoe, but before any pressure has been applied through the diaphragm to the shoe bottom.

After the pressure applying operation has been completed and the pressure has been relieved from the shoe bottom, the solenoid is de-energized to permit the wedge operating mechanism to be returned to its initial inoperative position with the wedge in a position in which the jack post is spaced from the last in the shoe and is located a sufficient distance away from the diaphragm to clear the top of the last irrespective of its height, this action preferably being effected, as herein illustrated, by resilient means, such as a spring, which operates automatically to return the parts to their initial inoperative positions after the solenoid has been de-energized, the jack post being returned to its elevated position before the jack as a whole is swung laterally into its inoperative position at one side of the pressure box, thereby eliminating any danger of the jack post being still in engagement with the last at the time the jack is returned to its inoperative position.

With the above and other objects and features in view, the invention will now be described in detail in connection with the accompanying drawings and will thereafter be pointed out in the claims.

In the drawings

Fig. 1 is a perspective view of a portion of the jack mechanism of a machine for applying pressure to shoe bottoms in which the present invention is embodied, shown with mechanism for controlling the jack;

Fig. 2 is a vertical section through the machine showing the jack engaging the last in a shoe mounted in the pressure box of the machine; and

Fig. 3 is an enlarged vertical section through the rear side plate of the machine with portions of the mechanism shown in elevation.

Before proceeding with a detailed description of the machine, a brief description of its mode of operation will be given. Referring to Fig. 2, the machine is provided with a pressure box 6 which is in communication with an upright cylinder 8 having a piston by movement of which water may be forced into the box when desired. A rubber diaphragm 10 forms the top of the pressure box, the diaphragm being held loosely in place and its middle portion resting upon a rigid plate 12. The plate 12 is adjustably supported by two cams 14 and 16 fastened respectively to rock-shafts 18 and 20 and interconnected by a link 22, the purpose of which is to facilitate height-wise adjustment of the plate 12 for shoes of different sizes.

Located above the diaphragm 10 is a plurality of plates; a back plate 24, a front plate 26, a rear side plate 28, and a forward side plate (not shown). The purpose of these plates is to mask and support against the pressure of the fluid from the cylinder that portion of the diaphragm which does not engage the shoe so that such portion will not be unduly distended during the pres-

sure applying operation with the consequent liability of bursting. The back mask plate 24 is adjustable but is stationary during the operation of the machine and normally the front plate and the two side plates are held in their open or retracted positions so that a shoe A on a last B with a sole C, for example, an unvulcanized rubber sole, positioned on its bottom may be passed through the opening enclosed by the plates into a position in which the shoe rests upon the diaphragm 10. When the shoe has been so placed, a treadle is depressed and the following movements take place.

The front plate 26 moves into engagement with the forward portion of the shoe and, at the same time, an upper casting 30 of the jack is swung from an inoperative position at one side of the pressure box into the position shown in Fig. 2 in which a jack post 32 carried by the casting 30 is located directly above the heel portion of the last B. The jack 30 and its operating mechanism, except for the construction of the jack post 32 and actuating mechanism associated therein, are substantially the same as those of the machine disclosed in the patent referred to and, accordingly, no detailed description of the jack will be necessary herein. The rigid plate 12 is now moved upwardly to force the toe portion of the shoe against the underside of the front plate 26, after which the rear side plate 28 and the forward side plate referred to are moved into engagement with the opposite sides of the shoe. The edges of all the mask plates are covered with a relatively thick layer of rubber 33 and the construction is such that, after the plates have been moved inwardly, there is substantially no space between the edges of the plates and the adjacent portions of the shoe, the edge of the stationary back plate 24 being curved to correspond approximately to the curvature of the back of the shoe at the point engaged. Consequently, a high water pressure may be applied to the diaphragm 10 without danger of bursting it by forcing a portion or portions of the diaphragm up between the plates and the shoe. After the shoe has been positioned on the diaphragm and the plates closed about the shoe as described, the piston in the cylinder 8 forces water into the pressure box 6 to wrap the diaphragm about the lower portion of the shoe and thereby press the sole firmly against the shoe bottom and bend the margin of the sole upwardly to press it against the lower margin of the shoe. After the pressure applying operation has been completed and pressure has been relieved from the shoe, the parts of the machine are returned to their initial normal positions of rest. The piston, the water reservoir, and the mechanism for operating the piston are, or may be, the same as are disclosed in the patent referred to and, accordingly, no further description of these mechanisms will be given herein.

The jack comprises the arm or casting 30 carried by a pair of upright threaded rods (not shown) provided on the machine whereby the casting may be adjusted vertically, the lower portions of these vertical rods being connected by a heavy casting 34 (Fig. 2) and the rod in the portion of the casting 34 shown in Fig. 2 being rotatable about its axis so that the jack may be swung from a position at one side of the diaphragm into a position in which the jack post 32 will be located directly above the heel portion of the last in the shoe resting on the diaphragm. The mechanism for swinging the jack in the

manner described is fully disclosed in the patent mentioned above to which reference may be had for a complete description of this mechanism.

The jack post 32 is connected to the casting 30 of the jack by means of a vertical shaft 36 fastened in a socket in the casting 30 by a screw 38. The upper portion of the jack post is provided with a vertical bore 40 into which the lower end of the shaft 36 extends, the jack post being secured to the shaft by a tapered pin 42, as shown in Fig. 2. The jack post 32 is spaced from the casting 30 by a rectangular sleeve or collar 44 secured to the shaft by a set screw 46 or any other suitable means.

As illustrated in Fig. 1, the jack post 32 is rectangular in shape and comprises an upper portion 48 and a lower portion 50 between which is interposed a wedge 52, the upper and lower surfaces of the wedge being inclined so that they converge toward the left and being engaged by correspondingly inclined surfaces formed respectively on the upper and lower portions 48 and 50 of the jack post. As shown in Fig. 1, the wedge 52 is cut away at its opposite sides to provide flanges 54 and 56, respectively, on its inclined upper and lower surfaces. The upper and lower surfaces of the wedge are also provided, respectively, with friction plates 58 and 60 which may be composed of any well-known frictionized material and which are secured to the inclined surfaces of the wedge, preferably by soldering or brazing. The angles of inclination of the upper and lower surfaces of the wedge 52 are such that, when augmented by the friction created by the plates 58 and 60, they will not permit the wedge to move or slip from its position between the jack post sections 48 and 50 even though relatively heavy pressure is applied to the lower end of the jack post. In other words, the coefficient of friction between the wedge 52 and the jack post sections is such that any pressure that may be applied to a shoe through the diaphragm 10 will be sustained or supported by the jack post without slippage of the wedge.

Referring to Fig. 1, the upper portion 48 of the jack post 32 has secured to its opposite sides by screws 61 a pair of T-shaped members 62, 64 which are provided respectively with inclined slots 68 and 70, into which the opposite flanges 54 on the upper surface of the wedge extend together with the overlying portions of the friction plates 58.

Each of the T-shaped members 62 and 64 is provided with a downwardly extending projection 72 which fits slidably into a vertical slot 74 formed in the outer surface of each of a pair of blocks 76 and 78 secured respectively to the forward and rear sides of the lower portion 50 of the jack post by screws 79, the blocks 76 and 78 also having inclined slots 80 and 82 formed respectively in their inner surfaces for receiving the flanges 56 on the lower surface of the wedge 52 together with the marginal portions of the friction plate 60 which underlie these flanges. This construction causes the lower portion 50 of the jack post to be supported by the wedge 52 through the flanges 56 in the slots 80, 82 and causes the portion 50 to be moved down or up toward or away from the diaphragm 10 when the wedge 52 is moved transversely or laterally of the post in a manner to be presently described, the projections 72 on the T-shaped members 62, 64 guiding the portion 50 in its heightwise movement by reason of their sliding fit in the vertical slots 74 in the blocks 76 and 78.

The lower end of the portion 50 of the jack post is provided with a contact member 84 which is pivoted on a pin 86 extending between ears on the post and is normally maintained with its lower face in a substantially horizontal plane by a pair of compression springs 88 (Fig. 2) interposed between the jack post and the contact member 84, the latter being thus able to pivot laterally of the post to adjust itself to the angle of the top of the last which it engages in supporting the shoe against pressure applied through the diaphragm 10.

The wedge 52 is moved laterally or crosswise of the jack post 32 by the following mechanism.

15 The upper portion 48 of the jack post is provided with an integral arm 90 which projects toward the left, as viewed in Figs. 1 and 2, and is slotted to provide a pair of ears between which is rotatably mounted on a pin 92 a bell-crank lever 94, the lower arm of the lever being pivotally connected by a link 96 to the small end of the wedge 52. The bell-crank lever has an upper arm 98 which is bifurcated at its outer end to provide ears which have a pin 100 rotatably mounted therein. Extending loosely through a hole in the pin 100 is a rod 102, the upper end of which is enlarged and is pivotally connected by a pin 104 to the core 105 of a solenoid 106, the latter being supported by a bracket 108 secured by screws 107 (Fig. 2) to the rectangular collar 44 previously referred to. The solenoid is wired in any usual manner by wiring 110 to a micro-switch 112 of any well-known commercial construction contained in a switch box or housing which in turn is secured to a bracket 114 fastened to a stationary portion 115 of the frame of the machine by screws 116.

The rod 102 is surrounded below the pin 100 by a spring 118 which is retained on the rod by a collar 120 fastened to its lower end. When the micro-switch 112 is closed, in a manner to be presently explained, the solenoid 106 is energized to elevate the core 105 and, through the spring 118, to rotate the bell-crank lever 94 yieldingly in a clockwise direction and thus move the wedge 52 toward the left, as viewed in Figs. 1 and 2, from the position indicated by the broken line 52' in Fig. 2 to a position which lowers the portion 50 of the jack post 32 until the contact member 84 thereon engages the top of the heel end of the last B in the shoe A, as illustrated in Fig. 2. In this way the jack post 32 is moved automatically into operative engagement with the last in the shoe after the shoe has been positioned on the diaphragm 10. After the pressure applying operation has been completed and pressure on the shoe has been relieved, the micro-switch 112 is opened automatically, as will be presently explained, to de-energize the solenoid and permit the parts to be returned to their initial or inoperative positions, the return of the wedge to the dotted position indicated in Fig. 2 being effected by a tension spring 122 connected at its lower end to a third arm 123 of the bell-crank lever 94 and, at its upper end, to the bracket 108 by a hook 124. Accordingly, when the solenoid is de-energized by the opening of the micro-switch 112, the parts are returned to their inoperative positions automatically by the tension spring 122.

The micro-switch 112 is operated in the following manner. The micro-switch is provided with a usual spring-pressed push button control member 126 (Fig. 3) inward movement of which closes the micro-switch to energize the solenoid,

the push button returning automatically to its open position when released by reason of its spring-pressed construction. The bracket 114 is provided forwardly of the micro-switch 112 with a rectangular block 128 having a vertical slot 130 formed in one side thereof covered by a plate 132 secured to the block by screws 134. Mounted for vertical sliding movement in the slot 130 is a bar 136 which is bifurcated at its opposite ends to provide ears thereon. Mounted on a pin 138 between the ears at the upper end of the bar 136 is a roll 140 and mounted on a pin 142 between the lower ears is a roll 144. The roll 144 is normally located forwardly of the rear side plate 28 which, as explained above, slides inwardly and outwardly with the other mask plates referred to relatively to the shoe to cover and protect the diaphragm 10 during the pressure applying operation. The bar 136 is normally held in its lowermost position (Fig. 1) by a spring 146 extending between a pin 148 in the bar and a pin 149 in the cover plate 132 of the block 128, this position being determined by the pin 148 engaging the lower end of a slot 150 in the cover plate (Fig. 3).

When the treadle is depressed to start the operation of the machine, the jack 30 is swung into position over the diaphragm 10, as explained above, to locate the jack post 32 above the shoe and, at the same time, the front plate 26 moves into engagement with the forward portion of the shoe. The side plates then move inwardly into contact with the opposite sides of the shoe, as previously explained, thereby causing the rear side plate 28 to pass under the roll 144 on the bar 136 and elevate this bar a distance sufficient to position the center of the roll 140 in substantial alignment with the axis of the push button 126 of the micro-switch 112, thereby closing the micro-switch and energizing the solenoid 106.

It will be seen from the foregoing that the micro-switch is closed by engagement of the rear side plate 28 with the lower roll 144 before fluid is forced by the piston into the pressure box 6 to distend the diaphragm 10 and cause it to be wrapped around the lower portion of the shoe. Consequently, the jack post 32, which at that time is located directly over the shoe, will be moved down by the wedge 52 to bring the contact member 84 into operative engagement with the last in the shoe before pressure is applied through the diaphragm 10 to the shoe bottom.

After the pressure applying operation has been completed and pressure on the shoe has been relieved, the side plates move outwardly away from the shoe before actuation of the mechanism for swinging the jack into its inoperative position at one side of the diaphragm. Accordingly, the side plate 28 will move out of engagement with the roll 144 to permit the bar 136 to descend to open the micro-switch, thereby deenergizing the solenoid 106 and permitting the spring 122 to return the bell-crank lever 84 and wedge 52 to their initial or inoperative positions, the initial position of the wedge 52, as stated, being indicated by the broken line 52' in Fig. 2. Since the lower portion 50 of the jack post is supported by the flanges 56 on the lower surface of the wedge 52, movement of the wedge to the right, as viewed in Fig. 2, will move the lower portion 50 of the jack post upwardly away from the last in the shoe and into its normal or inoperative position, the portion 50 being guided in a vertical path during its upward movement by the projections 72 in the vertical slots 74. After the

jack post 32 has been withdrawn from the shoe, the mechanism provided in the machine for swinging the jack 30 into its inoperative position at one side of the diaphragm operates automatically to swing the jack into such position, thereby returning all the parts to their inoperative positions and permitting the shoe and sole to be removed from the diaphragm. Since the jack post 32 is not withdrawn from engagement with the last until after the pressure applying operation has been completed and the pressure has been relieved to permit the diaphragm to return to its normal loose condition, the present construction insures against damage to the shoe or to the diaphragm such as might be caused by attempting to withdraw the jack post too soon. Moreover, since the jack post is automatically returned to its elevated position before the jack 30 is swung laterally away from the diaphragm into its position at one side of the diaphragm, there is no danger of causing damage to the shoe or to the jack post as there might be if the jack post were still in operative engagement with the last when the automatic mechanism for swinging the jack into its inoperative position started to operate. Consequently, the present invention not only insures against damaging the diaphragm, the jack or the shoe during the normal operation of the machine, but, at the same time, it permits shoes of different sizes to be operated upon successively by the machine without permitting any tilting or lifting of the heel portion of the shoe at the start of the pressure applying operation, such as would occur if the jack post 32 were not in actual operative engagement with the last before the diaphragm was distended by fluid from the piston to apply pressure to the shoe bottom.

While the invention has been disclosed herein, by way of illustration, as embodied in a machine for applying pressure to shoe bottoms of the type shown in the patent referred to above, the invention obviously has utility in other types of machines. Accordingly, it should be understood that the invention is not limited in the scope of its application to the particular machine or type of machine which has been shown and described herein.

Having thus described my invention, what I claim as new and desire to secure by Letters Patent of the United States is:

1. A machine for use in applying pressure to shoe bottoms having, in combination, means for applying pressure to the bottom of a shoe on a last, a member for engaging the last to support the shoe against said pressure, said member being normally spaced from the shoe, and yieldingly operated means for moving said member automatically into operative engagement with said last before pressure is applied to the shoe bottom.

2. A machine for use in applying pressure to shoe bottoms having, in combination, means for applying pressure to the bottom of a lasted shoe, a member movable relatively to the last in the shoe to support the shoe against pressure applied by said means, said member being normally located a distance away from the last, and means for automatically moving said member a variable distance controlled by the size of the last to bring said member into operative relation with said last before the pressure applying means applies pressure to the shoe bottom.

3. A machine for use in applying pressure to shoe bottoms having, in combination, means for

applying pressure to the bottom of a shoe on a last, a member movable toward and away from the shoe for engaging the last and supporting the shoe against said pressure, said member being normally located a distance away from the shoe, and yieldingly operated means for automatically moving said member toward the shoe a distance sufficient only to bring said member into operative engagement with the last and for withdrawing the member from the last.

4. A machine for use in applying pressure to shoe bottoms having, in combination, means for applying pressure to the bottom of a shoe on a last, a support, a member carried by the support for engaging the last and supporting the shoe against pressure applied by the pressure applying means, said member being normally located an indeterminate distance from the shoe, and means for automatically lengthening said member relatively to the support an amount sufficient only to bring it into operative engagement with the last irrespective of the size of said last.

5. A machine for use in applying pressure to shoe bottoms having, in combination, means for applying pressure to the bottom of a shoe on a last, a member for engaging the last and supporting the shoe against said pressure, said member being movable in one direction to engage the last and in another direction to withdraw from the last, and yieldingly operated means for moving said member automatically into engagement with the last before pressure is applied to the shoe bottom and for withdrawing said member from the last after pressure has been relieved from the shoe bottom, said means moving said member variable distances depending upon the sizes of the lasts operated upon.

6. A machine for use in applying pressure to shoe bottoms having, in combination, means for applying pressure to the bottom of a shoe on a last, a jack post movable into and out of engagement with said last for supporting the shoe against said pressure, said jack post being normally spaced from the last, and automatically operating means for moving the jack post a distance determined by the height of the last to bring said post into operative engagement with the last before the pressure applying means applies pressure to the shoe bottom and for returning said post to its inoperative position after the pressure applying operation has been completed and pressure has been relieved from the shoe bottom.

7. A machine for use in applying pressure to shoe bottoms having, in combination, means for applying pressure to the bottom of a shoe on a last, a jack normally positioned at one side of the pressure applying means and swingable into operative position over said means, a jack post on the jack for engaging the last in the shoe and supporting the shoe against pressure applied by said pressure applying means, said jack post being normally spaced an indeterminate distance above the last in the shoe, and means for automatically moving said jack post into operative engagement with the last after the jack has been swung into operative position over the pressure applying means but before said pressure applying means has applied pressure to the shoe bottom.

8. A machine for use in applying pressure to shoe bottoms having, in combination, means for applying pressure to the bottom of a shoe on a last, a support, a vertical member carried by the support for engaging the last and supporting the

shoe against pressure applied by said means, said member being normally located a predetermined distance above the pressure applying means, and yieldingly operating means for lengthening said vertical member automatically relatively to the support to bring said member into operative engagement with the last before pressure is applied to the shoe bottom, said means being also arranged to shorten said member automatically to remove it from the last after pressure has been relieved from the shoe bottom.

9. A machine for use in applying pressure to shoe bottoms having, in combination, means for applying pressure to the bottom of a shoe on a last, a member movable toward and away from the shoe for engaging the last to support the shoe against pressure applied by said means, said member being normally spaced from the shoe, and automatically operated means controlled by operation of said pressure applying means for moving said member into operative engagement with the last.

10. A machine for use in applying pressure to shoe bottoms having, in combination, means for applying pressure to the bottom of a lasted shoe, a member movable toward and away from the shoe for engaging the last in the shoe and supporting the shoe against pressure applied by said pressure applying means, said member being normally spaced a distance away from the shoe, and means controlled by operation of said pressure applying means for moving said member automatically into operative engagement with the last and for thereafter withdrawing the member away from said last.

11. A machine for use in applying pressure to shoe bottoms having, in combination, means for applying pressure to the bottom of a shoe on a last, a jack post movable heightwise toward and away from the shoe for engaging the last therein and supporting the shoe against pressure applied by the pressure applying means, said post being normally spaced an indeterminate distance above the shoe, and means controlled automatically by operation of said pressure applying means for lowering the jack post heightwise into operative engagement with said last before pressure is applied to the shoe bottom and for returning said jack post heightwise into its normal position after the pressure applying means has relieved the pressure on the shoe bottom.

12. A machine for use in applying pressure to shoe bottoms having, in combination, means for applying pressure to the bottom of a shoe on a last, a jack, a post carried by the jack and normally located a predetermined distance away from the pressure applying means, said post being arranged to engage the last and support the shoe against pressure applied by said pressure applying means, a wedge interposed between the jack and jack post, and yieldingly operated means for automatically moving the wedge in one direction to bring the jack post into operative engagement with the last and in another direction to withdraw the post from the last.

13. A machine for use in applying pressure to shoe bottoms having, in combination, means for applying pressure to the bottom of a shoe on a last, a jack, a post carried by the jack and normally spaced an indeterminate distance from the shoe for engaging the last and supporting the shoe against pressure applied by said pressure applying means, a wedge interposed between the jack and jack post and arranged for sliding movement laterally thereof, a bell-crank lever con-

nected to said wedge, yieldingly operating means connected to said bell-crank lever for automatically effecting rotation of said bell-crank lever and thereby causing sliding movement of the wedge in a direction and for a distance sufficient only to move the jack post into operative engagement with the last irrespective of its size before pressure is applied to the shoe bottom, and means arranged to move the wedge in an opposite direction to return the jack post to its initial position after pressure has been relieved from the shoe bottom.

14. A machine for use in applying pressure to shoe bottoms having, in combination, means for applying pressure to the bottom of a shoe on a last, a jack, a post carried by the jack for engaging the last and supporting the shoe against pressure applied by the pressure applying means, said post being normally spaced an indeterminate distance above the shoe, a wedge interposed between the jack and jack post and arranged for movement laterally thereof, a bell-crank lever having one arm connected to the wedge, a solenoid connected to another arm of said bell-crank lever, means controlled by operation of the pressure applying means for energizing the solenoid to move the bell-crank lever automatically in a direction to cause the wedge to bring the jack post into operative engagement with the last, and resilient means for thereafter returning the bell-crank lever and wedge to their initial positions to withdraw the jack post from the last and return it to its normal position.

15. A machine for use in applying pressure to shoe bottoms having, in combination, means for applying pressure to the bottom of a shoe on a last, a jack, a post on said jack for supporting the shoe against said pressure, said post being normally spaced from the shoe, a wedge interposed between the jack and jack post, a bell-crank lever having one arm connected to the wedge, a solenoid yieldingly connected to the other arm of said bell-crank lever, means controlled automatically by operation of the pressure applying means for energizing the solenoid to swing the bell-crank lever to move the wedge in a direction to bring the jack post into operative engagement with the last before pressure is applied to the shoe bottom, and means for returning the wedge and solenoid to their initial positions to withdraw the jack post from the last after pressure has been relieved from the shoe bottom.

16. A machine for use in applying pressure to shoe bottoms having, in combination, a flexible diaphragm for applying pressure to the bottom of a shoe on a last, a jack, a post on the jack for engaging the last and supporting the shoe against said pressure, said post being normally spaced from the shoe, means located outside the diaphragm and having an opening therein large enough for the shoe to pass through, mechanism for operating said last-named means to decrease the size of said opening, and means controlled by operation of said last-named means for moving the jack post automatically into operative engagement with the last before pressure is applied by said diaphragm to the shoe bottom.

17. A machine for use in applying pressure to shoe bottoms having, in combination, a pressure box, one wall of which comprises a flexible diaphragm through which pressure is applied to

the bottom of a shoe on a last, a jack, a post on the jack for engaging the last in the shoe and supporting the shoe against pressure applied through said diaphragm, said post being normally spaced an indeterminate distance from the shoe, a plurality of movable members located outside the box adjacent to said diaphragm and having an opening therein large enough for the shoe to pass through, mechanism for moving said members to decrease the size of the opening and position said members close to the shoe, and means controlled automatically by operation of said members for moving the jack post into operative engagement with the last.

18. A machine for use in applying pressure to shoe bottoms having, in combination, a pressure box, one wall of which comprises a flexible diaphragm through which pressure is applied to the bottom of a shoe on a last, a jack movable from a position at one side of the shoe into a position over the shoe, a post carried by said jack for engaging the last in the shoe and supporting it against pressure applied through said diaphragm, said post being normally spaced an indeterminate distance from the shoe, a plurality of plates mounted outside the pressure box adjacent to the diaphragm and providing an opening large enough to permit the shoe to pass through, mechanism for moving said plates relatively to the diaphragm to decrease the size of the opening and position the plates close to the shoe, means controlled by the operation of said plates for moving the jack post into operative engagement with the last before pressure is applied to the shoe bottom, and separate means for returning the jack post to its inoperative position after pressure has been relieved from the shoe bottom.

19. A machine for use in applying pressure to shoe bottoms having, in combination, a pressure box, one wall of which comprises a flexible diaphragm, a jack, a post on said jack normally spaced a predetermined distance above the diaphragm, a plurality of movable plates located outside the box adjacent to the diaphragm and having an opening therein large enough for the shoe to pass through, mechanism for moving the plates transversely of the diaphragm to decrease the size of said opening, a wedge interposed between said jack and jack post, a solenoid connected to the wedge, a micro-switch, means controlled by movement of said plates transversely for closing the micro-switch to energize the solenoid and thereby slide the wedge between the jack and jack post in a direction to move the jack post downwardly into operative engagement with the top of the last in the shoe before pressure is applied through said diaphragm to the shoe bottom, and means for returning the wedge and jack post automatically to their inoperative positions after pressure has been relieved from the shoe bottom.
